UNITED STATES PATENT OFFICE.

ALBERT G. HOBAN AND RALPH L. MARQUIS, OF DAYTON, OHIO.

ELECTRIC LAMP.

1,074,949.

Specification of Letters Patent.

Patented Oct. 7, 1913.

Application filed December 10, 1912. Serial No. 735,927.

To all whom it may concern:

Be it known that we, ALBERT G. HOBAN and RALPH L. MARQUIS, citizens of the United States, residing at Dayton, in the 5 county of Montgomery and State of Ohio, have invented certain new and useful Improvements in Electric Lamps, of which the following is a specification.

This invention relates to new and useful 10 improvements in protecting and reflecting means for incandescent electric lamps.

The principal object of the invention is to provide a casing for incandescent lamps, which is so constructed as to prevent the 15 exposed portions of the lamp being subjected to the deteriorating influence of water and other elements.

A further object of the invention is to provide for the lamp bulb, a reflecting 20 shield so constructed and equipped as to vary at will the color of the light emitted.

Other important and incidental objects will be brought out in the following specification and subjoined claims.

25 In the accompanying drawings, Figure 1 is a sectional elevation of an incandescent electric lamp provided with our improved protecting and reflecting means. And Fig. 2 is a top plan view of the same.

30 Throughout the specification and drawings, similar reference characters denote corresponding parts.

In the detailed description of our invention, 1 designates a cup-shaped receptacle 35 adapted to receive a lamp socket 2. Passing through the base of the receptacle 1, and entering the lamp socket 2, are leading-in wires 3 and 4 which supply the lamp with current. Extending around the upper portion 40 of the receptacle 1 is an annular flange 5, and between the latter and the top of the receptacle is a threaded portion 7 which permits the said receptacle to be screwed into an aperture in a supporting plate 6. This 45 plate 6 is usually the panel of an electric sign, and in order that it may have sufficient strength and rigidity for that purpose it is preferably constructed of galvanized iron.

50 The receptacle 1 is screwed into the plate 6 until the flange 5 bears tightly against the bottom surface of said plate. When so positioned in the plate 6, the threaded portion 7 of the receptacle 1 will extend a short 55 distance above said plate. The receptacle is

now ready to receive an incandescent lamp 8 having a neck portion 9 which is adapted to be screwed into a socket 2 from the opposite side of the plate 6.

Adapted to be fitted over the lamp 8 is a 60 conical shield or cap 10, which may be constructed of porcelain or other material which will give the necessary protecting and reflecting properties. The shield 10 is internally screw-threaded at its end of smallest 65 diameter in order that it may be received by the threaded portion 7 of the receptacle 1 after said threaded portion has passed through the plate 6. After the receptacle 1 is in place on said plate and the shield 10 is 70 united thereto, these elements form a water and weather proof covering for the socket 2, and there is no possibility of water or other foreign matter seeping through the points of connection of the shield, receptacle and plate. Accordingly, the damage and injury due to rust and other chemical decomposition when an electric sign is exposed to the weather, is avoided in so far 75 as the lamp and its terminals are concerned. 80

Near its end of largest diameter and projecting from the inner surface of the shield 10, is an annular flange or ledge 11 upon which is adapted to rest a circular colored glass 12. This glass is removable to make 85 place for a similar glass of another color, and is held in place by a split ring 13 having upwardly projecting ends 14 adapted to be grasped by the fingers. The tension of the ring 13 is sufficient to force it tightly 90 into an annular recess 15 in the shield 10 immediately above the glass 12, to hold the latter firmly in place on the ledge 11. It will now be seen that the light emitted by the lamp 8 will be directed outwardly by the side 95 walls of the shield 10, and colored as it passes through the glass 12. It is thus possible to color a character which a lamp 8 may assist in forming in an electric sign.

In operation, the receptacle 1 is screwed 100 into an aperture in the plate 6 until the flange 5 bears tightly against the lower surface of said plate. An incandescent lamp 8 is then screwed into the socket 2 within the receptacle 1, and the shield 10 tightly 105 screwed onto the threaded portion 7 of said receptacle. The receptacle and shield will now co-operate to protect the socket and lamp from the deteriorating influence of the weather. A colored glass is now placed 110

against the ledge 11, and held in place by the ring 13, to color the light emitted by the lamp.

We do not wish to be limited to the details 5 of construction herein shown and described, and any alterations or modifications may be made therein to suit different conditions of use.

- Having described our invention, we claim:
- 10 1. In an electric sign, an electric lamp socket, an electric lamp, a receptacle for said socket, a conical shield adapted to be screwed upon the upper end of said receptacle to surround said lamp, an annular ledge projecting from the interior surface of said shield near its outer end, a colored glass resting upon said ledge to color the light emitted by the lamp, and a split ring 15 the outer circumferential portion of which rests within an annular recess in the shield and the inner circumferential portion of which bears upon the glass to hold the latter firmly upon the ledge, substantially as described.
  - 20 2. In an electric sign, an electric lamp, an

electric lamp socket, a receptacle in which said socket is inclosed, a supporting plate, an aperture in said plate to receive the receptacle, an annular flange projecting from the upper, outer surface of said receptacle 30 and adapted to bear against the plate, said receptacle having a circumferential threaded portion above said flange, said threaded portion extending beyond the plate when the flange is in contact with it, a conical shield 35 surrounding said lamp, said shield having its end of smallest diameter threaded to receive the threaded portion of said receptacle, and a removable colored glass disposed in the outer end of said shield to color the 40 light emitted by the lamp, substantially as described.

In testimony whereof we have hereunto set our hands this 7th day of December, A. D. 1912.

ALBERT G. HOBAN.
RALPH L. MARQUIS.
